SAFETY WALL AND DESK KNIFE

Bennie Ward Anderson, Cisco, Tex., assignor of
one-fourth to Taylor A. Sherrill, Rising Star,
Tex.

Application February 3, 1934; Serial No. 709,657

1 Claim. (Cl. 30—14)

This invention relates to cutting tools and more particularly to a means for cutting rope, cord or the like.

An object of this invention is to provide a cutting device in the form of a keen edged blade which is so constructed that it can be mounted at a convenient point and which embodies features whereby the keen edge of the device is protected so as to prevent accidental injury from the blade.

Another object of this invention is to provide an exceedingly simple device of this kind which is so constructed that the blade will be rigidly held in operative position and the mounting means for the blade can be secured to any convenient and relatively rigid support.

The above and various other objects and advantages of this invention will in part be described and in part be understood from the following detailed description of the present preferred embodiment, the same being illustrated in the accompanying drawing wherein:—

Figure 1 is a plan view of a device constructed according to the embodiment of this invention, showing the device mounted on a support which is shown in fragmentary form.

Figure 2 is a detail side elevation of the device.

Figure 3 is a sectional view taken on the line 3—3 of Figure 2.

Figure 4 is a detail side elevation of the cutting blade.

Referring to the drawing wherein like numerals of reference designate corresponding parts throughout the views, the numeral 10 designates generally the support which may be in the form of a wall, desk, bench or the like, and this support 10 may be either horizontal or vertical or on any other angle relative to the horizontal or vertical.

Secured to this support 10 is a blade mounting means in the form of a pair of base members 11 which are secured to the support 10 as by screws or securing members 13. A substantially U-shaped blade supporting member 12 is integral with the base plates or members 11 and this blade supporting member 12 has cut out portions or slots 14 extending inwardly from one end thereof, which end is the operative end of the device.

The bight of the blade supporting member 12 is reduced and provided with a second U-shaped member 15 which is integral with the U-shaped member 12, and this U-shaped member 15 has adjacent one end thereof a headed pin 16 extending transversely therethrough at a point inwardly from the inner and outer edges thereof.

This U-shaped member 15 extends throughout the length of the base members 11 and a blade, generally designated as 17, is adapted to be removably disposed within the blade engaging member 15.

The blade 17 comprises a relatively thick or heavy body 18 provided at one end with a notch 19 opening through said one end of the body 18 and the pin 16 is adapted to be received in this slot 19. The slot 19 is relatively long and the pin 16 is disposed at a point intermediate the ends of the blade engaging member 15 so that when the body 18 is disposed between the parallel legs of the member 15, the blade will be firmly held within this member.

The forward end of the body 18 is provided with an offset portion 20 which limits the movement of the blade 17 in one direction within the blade engaging member 15. This blade 17 is provided with a keen edge or knife 21 extending along one edge thereof, which keen edge 21 is adapted to be disposed between the parallel legs of the supporting member 12 and inwardly of the parallel legs of the blade engaging member 15. The blade 17 is also provided adjacent the forward end thereof with a hole 22 within which a removing implement or the like may be disposed in the event the blade 17 sticks within the clamp or blade engaging member 15. The forward end of the supporting member 12 is rounded off, as at 23, and this rounded off portion constitutes a guide means which is adapted to guide a cord or the like toward the keen edge 21 of the blade 17. This guide portion 23 also acts as a guard for the keen edge 21 so as to prevent injury from the blade 17 while at the same time permitting a cord or other flexible member to be engaged with the keen edge 21 as the cord is pulled longitudinally of the blade and between the guide or guard members 23.

In the use of this device, the support including the base members 11, the member 12 and the blade clamping or engaging member 15 is adapted to be mounted by means of the securing members 13 on a suitable support such as a desk, wall or the like, and where the support is mounted in a relatively upright position, the guard portion 23 of the device is disposed uppermost. The cord which it is desired to cut by the blade 21 can be drawn downwardly over the curved portions or guide member 23 which will move the cord toward the keen edge 21. The cord, if desired, can be drawn for substantially the entire length of the blade 17 between the parallel legs of the supporting member 12 as the cut out portions 14 provide side guards and these guards are disposed in spaced 55

relation to the blade 17. The blade 17 is so constructed that it can be readily removed from the support so that it can be sharpened. Preferably the upper end of the blade 17 is rounded off, as 5 at 24, so that this rounded portion will coat with the rounded portions 23 in guiding the cord toward the keen edge 21.

It is, of course, understood that various changes and modifications may be made in the details of 10 construction and design of the above specifically described embodiment of this invention without departing from the spirit thereof, such changes and modifications being restricted only by the scope of the following claim.

15 What is claimed is:—

A device as set forth comprising a blade having a rounded end and a notch extending inwardly from the opposite end intermediate the longitudi-

dinal edges thereof, a U-shaped blade engaging member, a pin extending through the parallel legs of said blade engaging member and disposed intermediate the ends of the member, said pin being adapted to engage in the notch of the blade to hold the blade against movement in the direction of the parallel legs of the blade engaging member, a stop carried by the blade and engaging one end of the blade engaging member to limit the insertion of the blade in the member, and a pair of guard members disposed on opposite sides of the blade and in spaced parallel relation thereto, said guard members having rounded upper end portions coacting with the rounded end of the blade to guide an article toward the keen edge of the blade. 5 10 15
